UNITED STATES PATENT OFFICE

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY

FASTENING INSERTING MECHANISM

Application filed March 29, 1929. Serial No. 350,901.

This invention relates to fastening inserting mechanisms and is illustrated herein as embodied in a peg inserting implement adapted to be held in the hand of an operator and to be moved from one spot to another to insert pegs through the upper and into the insole of the heel and toe portions of a shoe the upper of which has been wiped into lasted relation to an insole on a last upon which the shoe is mounted in a bed lasting machine. Thus the illustrated implement is intended to take the place of the ordinary hand tacker, inserting fiber pegs instead of tacks. It should be understood, however, that the invention is not limited in its utility to embodiment in a hand implement. Obviously in various of its aspects it may be embodied in fastening inserting mechanisms or machines of other characters.

It is an object of the present invention to provide an improved fastening inserting implement constructed and arranged to drive fastenings into shoe parts. The illustrated implement inserts fiber pegs severed from a strip of fiber fastening material such as paper twine. It has been found necessary to form holes in the shoe parts for the reception of these fiber pegs and the problems to be solved in providing a satisfactory fastening inserting implement have, accordingly, been complicated by the necessity of providing the implement with an awl and awl operating means in addition to the peg presenting means and the driver and driver operating means.

With these circumstances in view, an important feature of the invention comprises an improved construction in which an awl bar and a driver bar are mounted for reciprocating movement toward and from a work piece, connections between the two being provided whereby the early portion of the movement of the driver bar toward the work piece is effective to move the awl bar toward the work piece, causing the awl to form fastening receiving holes in the work piece and thereafter, during continued movement of the driver bar, withdrawing the awl bar to a position such that the awl does not interfere with the insertion by the driver of a fastening in the hole formed by the awl.

In the illustrated construction, and in accordance with this and other features of the invention, the awl bar carries a latch member, which, during the early movement of the driver bar toward the work piece, moves the awl bar in a direction to move the awl into alignment with the driver and then to thrust the awl into the work piece in the line of drive, forming a fastening receiving hole therein. Then the latch member is tripped and, as the driver bar continues its movement toward the work piece, the awl bar is withdrawn by power transmitted to it from the driver bar through a rocking member which serves also to supply power for the severing of a peg from the strip of peg material and to present that peg to the driver to be inserted thereby in the hole formed by the awl.

If it should happen that the driver bar is not reciprocated through its full stroke a peg might be left in the nozzle of the implement, causing damage to the awl upon the next attempt to operate the implement. Accordingly, another feature of the invention comprises improved mechanism illustrated as a latch arranged to prevent the driver bar (which, as disclosed herein, takes the form of a spring returned plunger) from returning to its normal inoperative position if it is moved through less than its complete normal path.

With the above and other objects and features in view the invention will now be described with reference to the accompanying drawings and pointed out in the claims.

In the drawings:

Fig. 1 is a side elevation of a peg inserting implement embodying the present invention, the front of the casing of the implement being removed to show the interior mechanism;

Fig. 2 is a view generally similar to Fig. 1 but showing the parts in the position which they occupy at the conclusion of the fastening inserting stroke of the driver bar or plunger of the implement;

Figs. 3 and 4 are longitudinal sections on the lines III—III and IV—IV respectively of Fig. 1;

Fig. 5 is a side elevation on a larger scale

than Fig. 1 and looking in the opposite direction, part of the casing being broken away; and

Figs. 6 and 7 are side elevations of the 5 lower portion of the device with the front of its casing removed and looking in the same direction as Fig. 1, showing particularly the means for severing pegs from a strip of peg material and for presenting pegs in line with 10 the driver and the throat opening of the implement, Fig. 6 showing the parts in the position which they occupy as the awl finishes its work penetrating movement and Fig. 7 showing the parts after the awl has been withdrawn from the work piece and with a fastening in the line of drive.

The illustrated peg inserting implement is provided with a hollow casing 10 adapted to be held in the hand of an operator and 20 supporting a reel 12 (Fig. 1) on which is wound a strip of fiber fastening material such as paper twine 14. Mounted for vertical reciprocation in ways formed in the casing 10 is a plunger 16 constituting a driver bar and 25 having a driver 18 secured to its lower end. A spring 20 is housed in the plunger 16, bearing at its upper end against a plug 22 threaded into the head 24 of the plunger and at its lower end against a channel-shaped member 30 straddling a pin 28 passing through slots 30 formed in the walls of the plunger and supported at its ends by the casing 10. The spring 20 thus serves normally to hold the 35 plunger 16 in elevated position, as shown in Fig. 1, and permits it to be forced downwardly to the position shown in Fig. 2 when struck by a maul such as is commonly used to depress the plunger of a hand tacker.

An awl bar 32 is also mounted for movement in the casing 10 toward and from a work piece to which the nozzle 34 of the implement is presented. To guide the awl bar 32 in its movement it is provided with a pair of slots 36 the upper portions of which are 40 parallel to the direction of movement of the plunger or driver bar 16 and the lower portions of which are inclined downwardly and to the left, as shown in Figs. 1, 2, 6 and 7. Received in each of the slots 36 is a stud 38 surrounded by a wear member or roll 40 of a diameter which is an easy sliding fit in the slot 36. Thus it will be seen that as the awl bar 32 starts to move downwardly from the position of Figs. 1 and 7 to the position 55 of Figs. 2 and 6 it is first moved in a direction having a transverse component to the left until the awl 42, which is rigidly secured to as by being formed integrally with the lower end of the awl bar 32, is in alinement with 60 the driver passage 44 of the nozzle 34. By this time the vertical portions of the slots 36 are in engagement with the rolls 40 and the awl bar 32 moves straight down projecting the awl 42 from the nozzle 34, as shown in 65 Fig. 6, thus forming a fastening receiving

hole in the work piece to which the nozzle 34 of the implement has been presented. This takes place during the first quarter or thereabouts of the downward movement of the plunger 16.

In order to cause the downward movement of the plunger 16 to move the awl bar 32 in the manner just described, detachable connections between the two are provided comprising a latch member 46 (Figs. 1 and 2) pivoted at 48 to the awl bar 32 and provided near its lower end with a surface 50 positioned, when the plunger is in its inoperative position, beneath a hardened block 52 secured to the plunger 16 near the lower end thereof. A spring 54, anchored at its upper end to the latch member 46 and bearing at its lower end against a stud 56 secured to the awl bar 32, is provided with a coil surrounding the pivot 48 and tends to rock the latch member 46 in a clockwise direction, as viewed in Fig. 1, thus maintaining engagement between the surface 50 of the latch member and the lower surface of the block 52. After the awl bar 32 has moved downwardly a short 80 distance from the position shown in Fig. 1 an inclined surface 58 formed on the latch member 46 near its upper end strikes a similar inclined cam surface 60 formed on a block 62 secured to the casing 10 thereby rocking the latch member 46 in a counter-clockwise direction, as viewed in Fig. 1, and thus breaking the connection between the surface 50 of the latch member 46 and the lower surface of the block 52 so that the plunger 16 is free to 85 continue its downward movement without causing further downward movement of the awl bar 32.

By this time, it will be remembered, the awl 42 has formed a fastening receiving hole 105 and is ready to be withdrawn from the work piece and returned to its original position where it is out of alinement with the driver 18 and will not interfere with the insertion of a fastening in the hole by the driver 18. Accordingly, the plunger 16 is provided with a cam surface 62 near its lower extremity arranged, as the plunger 16 moves downwardly, to strike the left hand portion of a combined gear and cam member 64 mounted 110 on a pin 66 supported by the casing 10. The right hand portion of the member 64 is provided with a cam surface 68 arranged, as the member 64 is moved by the cam surface 62 in a counter-clockwise direction from the position shown in Fig. 1 to the position shown in Fig. 2, to contact with a roll 70 mounted upon the stud 56 and by its continued movement to return the awl bar to its original position, as shown 115 in Fig. 2.

During this return movement of the awl bar 32 the driver 18 continues its downward movement and by the time the awl bar has 120 been returned to its original position the 125

driver has reached the position shown in Fig. 7. In the meantime a peg 72 (Fig. 7) has been severed from the fastening material 14 and has been brought into the line of drive by mechanism which will now be described.

In the lower portion of the casing 10 is housed a conduit or tube 74 through which the fastening material 14 passes. The lower end of the tube 74 is in alignment with a hole 76 formed in a web 78 at the lower end of the casing 10. Pivoted to the casing 10 below the web 78 and substantially at the upper end of the nozzle 34 is a fastening shearing and transfer member 80 provided with a hole arranged to receive the strip of fastening material 14 when the member 80 is in its left hand position, as shown in Fig. 6, and to shear a peg from the strip of material as it moves to the right to the position shown in Fig. 7 thus bringing the peg into alignment with a driver passage formed in the web 82 and having its upper end flared, as shown at 83 in Figs. 6 and 7.

The member 80 is slotted at its lower right-hand portion, as shown in Figs. 6 and 7, to prevent interference with the upper portion of the awl 42. A lever 84 is secured to the member 80 and is provided at its upper end with a gear segment 86 meshing with a gear segment 88 formed on the combined gear and cam member 64 so that the same rocking movement of the member 64 is effective both to return the awl bar 32 and to move the peg severing and transferring member 80 to the position shown in Fig. 7 thus presenting a peg for insertion by the driver 18. A spring 90 supported by a pin 92 carried by the casing 10 bears at one end against the interior of the casing 10 and at the other end against the lever 84 tending to move the lever 84 and the peg severing and transferring member 80 in a counterclockwise direction from the position shown in Fig. 2 to the position shown in Fig. 1 and is effective to accomplish this purpose during the return movement of the plunger or driver bar 16.

Means, also operated by the downward movement of the plunger 16, is provided to feed the fastening material 14 forward to the member 80. This comprises a feed dog 94 (Fig. 5) carried by a bell crank lever 96 fulcrumed at 98 to a block 100 provided at its lower edge with a flange 102 located in a transverse slot near the lower end of the driver bar 16. A spring 104 tends to rock the bell crank lever 96 in a counterclockwise direction, as viewed in Fig. 5, thus gripping the fastening material 14 between a surface of the feed dog 94 and a cooperating surface 106 formed on the block 100. The lower end of the depending arm of the bell crank lever 96 is provided with a surface 108 arranged early in the downward movement of the driver bar 16 to engage a roll 110 mounted on a pin 112 adjustably clamped in a slot 114

formed in the casing 10, thereby rocking the bell crank lever 96 in a clockwise direction, as viewed in Fig. 5, against the spring 104 and thereby releasing the dog 94 from the fastening material 14. Thus only a short portion of the stroke of the driver bar or plunger 16 is effective to feed the strip of fastening material 14 and this occurs during the early part of the stroke.

To prevent retrograde movement of the strip of fastening material 14 a second dog 116, similar to the feed dog 94, is carried by a lever 118 fulcrumed at 120 to an adjustable block 121 carried by the casing 10 and clamping the fastening material 14 against a stationary surface carried by the block 121 in such a manner as to permit feeding movement by the dog 94 but to prevent movement of the fastening material in a reverse direction.

The implement is provided with a safety device to prevent damage to the awl if a peg should become jammed in the driver passage. This device is arranged to prevent the return of the plunger 16 to its normal inoperative position at a time when it has been moved through a path less than its complete normal stroke. Thus if the driver is moved only part way through the nozzle 34, leaving a peg in the nozzle, the plunger 16 will fail to return to its inoperative position and the operator will be warned that something is wrong. He will then proceed to clear the obstruction, then move the plunger 16 through its complete stroke, after which it will return to the position of Fig. 1. This safety device comprises a latch block 122 (Fig. 4) secured to the lower part of the driver bar or plunger 16 and provided with a plurality of transverse grooves 124 in a surface which engages a slide bar 126 mounted for vertical movement through a short path in ways formed in casing 10. The slide bar 126 is provided with a slot 128 through which projects a spring latch member 130 secured at 132 to the casing 10. A portion 134 of the slide bar 126 overlies a portion of the latch member 130, permitting the latter to project into the path of movement of the latch block 122 when the slide bar 126 occupies its upper position which it does at all times except when the plunger 16 is completing its downward stroke and thereafter is making its return stroke upwardly. The slide bar 126 is provided with a lug 136 at its upper end and with another lug 138 at its lower end, these lugs projecting into the path of the movement of the latch block 122. Thus when the driver 16 and the latch block 122 approach the lower end of their paths of movement, the slide bar 126 is moved a short distance downwardly by the impact of the latch block 122 against the lug 138, the portion 134 of the slide bar 126 moving the spring latch member 130 to the left, as viewed in Fig. 4, out of the path of movement

125
130

of the latch block 122 so that the plunger 16 is free to return to its normal inoperative position. If, however, the downward movement of the plunger 16 is arrested before the 5 latch block 122 reaches the lug 138 the latch member 130 will catch in one of the grooves 124 of the latch block 122 and will prevent the return of the plunger 16. This, of course, 10 will take place at any time when the implement has been operated in such a manner that the driver 18 has failed to force a peg out of the nozzle 34 of the implement by reason of failure to complete the downward stroke of the plunger 16. The upper end of 15 the latch block 122 hits the lug 136 moving the slide bar 126 upwardly and releases the spring member 130 at the end of the upward stroke of the plunger 16.

In using the illustrated peg inserting implement the operator grips it in his hand, bringing its nozzle 34 into engagement with the upper of a shoe in which a peg is to be inserted. He then strikes the upper end of the plunger 16, causing the latter to move 20 downwardly from the position shown in Fig. 1 to the position shown in Fig. 2. As the plunger 16 is depressed the feed dog 94 is operated to feed the strip of peg material 14 downwardly, thrusting the end of the strip 25 into the severing and transferring member 80 which at that time occupies the position shown in Fig. 6. Then, when the surface 108 of the bell crank lever 96 reaches the stud 114, the feed dog 94 is released so that further movement of the plunger 16 does not 30 affect the strip of fastening material 14. During this same portion of the downward movement of the plunger 16 the awl bar 32 has been moved to the left, as viewed in 35 Figs. 1 and 2, and downwardly, thrusting the awl 42 through the nozzle, as shown in Fig. 6, in a path the portion of which beyond the outer or lower end of the nozzle coincides with the line of drive and forming a 40 fastening receiving hole in the work piece. When this has taken place the latch 46, which until this time has formed an operative connection between the plunger 16 and the awl bar 32, is released by engagement of 45 its surface 58 against the cam surface 60 of the block 62. Next the combined gear and cam member 64 is engaged by the cam surface 62 of the plunger 16 and is rocked from the 50 position of Fig. 1 to the position of Fig. 2 thus causing the member 80 to sever a peg and to transfer it to driving position, as shown in Fig. 7. At the same time the surface 68 of the member 64, by engagement 55 with the roll 70, lifts the awl bar 32 and returns it to its original position, thus moving the awl 42 out of way of the driver 18. Continued downward movement of the plunger 16 moves the driver 18 through the driver passage into engagement with the fastening 72, forcing the latter through the nozzle 34 and into the hole formed by the awl 42 in the work piece. In this connection it 70 may be noted that the left-hand surface of the awl itself, (as viewed in Fig. 7) forms a portion of the wall of the driver passage in the nozzle 34 since the latter is slotted to permit the transverse movement of the awl. Near the end of the downward movement of the plunger 16 and the driver 18 the latch block 122, which, it will be remembered, is secured to the driver bar 16, engages the lug 138 of the slide bar 126, moving the slide bar 126 downwardly and thus causing the portion 134 of the slide bar 126 to force the spring latch member 130 out of the path of movement of the latch block 122 so that the plunger 16 can be returned to its inoperative position by the spring 20.

Having thus described my invention what I claim as new and desire to secure by Letters Patent of the United States is:

1. Fastening inserting mechanism comprising a driver bar reciprocable toward and from a work piece, a driver carried at the lower end of the driver bar, an awl bar, an awl integral with the lower end of the awl bar, a nozzle through which the awl and driver are reciprocated, and connections between the awl bar and the driver bar constructed and arranged to reciprocate the awl bar during the early portion of the movement of the driver bar toward the work piece in a path the portion of which beyond the outer end of the nozzle coincides with the line of drive, thereby causing the awl to form a fastening receiving hole in the work piece and to be withdrawn therefrom without interference with the insertion of a fastening in said hole by the driver during a later part of the movement of the driver bar.

2. Fastening inserting mechanism comprising a driver bar mounted for longitudinal reciprocation, a driver carried by the lower end of the driver bar, an awl bar mounted for lengthwise movement, an awl rigidly connected to the lower end thereof, connections between the awl bar and the driver bar constructed and arranged to cause the early part of the movement of the driver bar toward a work piece to thrust the awl into the work piece in a path coincident with the line of drive, forming fastening receiving holes therein, and then to withdraw the awl from the work piece, and means for presenting a fastening for insertion by the driver upon continued movement of the driver bar.

3. A fastening inserting mechanism comprising a driver bar reciprocable toward and from a work piece, a driver carried at the lower end of the driver bar, an awl positioned normally out of alignment with the driver, and connections between the driver bar and the awl constructed and arranged to move the awl into alignment with the driver and then toward and into the work piece.

thereby forming a fastening receiving hole in the work piece during the early part of the movement of the driver bar toward the work piece, a cam, and means for rotating 5 the cam and thereby withdrawing the awl from the work piece.

4. A fastening inserting mechanism comprising a driver bar reciprocable toward and from a work piece, a driver carried at the 10 lower end of the driver bar, an awl bar, an awl carried by the awl bar and rigid therewith positioned normally out of alinement with the driver, means for moving the awl into alinement with the driver and toward 15 and into the work piece thereby forming a fastening receiving hole in the work piece, said awl moving means including a latch forming a connection between the awl bar and the driver bar constructed and arranged 20 to cause the early portion of the movement of the driver bar from its inoperative position toward the work piece to cause work-piercing movement of the awl bar, and a cam pivoted to a stationary part of the mechanism and 25 operated by continued movement of the driver bar to withdraw the awl.

5. A fastening inserting mechanism comprising a driver bar reciprocable toward and from a work piece, a driver carried by the 30 lower end of the driver bar, an awl, connections between the driver bar and the awl constructed and arranged to move the awl toward and into the work piece thereby forming a fastening receiving hole in the work 35 piece during the early part of the movement of the driver bar toward the work piece, a cam, and means for rotating the cam thereby withdrawing the awl from the work piece and moving it out of alinement with the 40 driver.

6. Fastening inserting mechanism comprising a driver bar reciprocable toward and from a work piece, a driver carried at the lower end of the driver bar, an awl bar, an 45 awl integral therewith and normally out of alinement with the driver, connections between the awl bar and the driver bar including a latch constructed and arranged to move the awl bar during the early portion of the 50 movement of the driver bar toward the work piece, thereby bringing the awl into alinement with the driver, causing the awl to form a fastening receiving hole in the work piece and to be withdrawn therefrom, and 55 a cam pivoted to a stationary part of the mechanism and rocked by the continued movement of the driver bar thereby moving the awl back to its normal position without interference with the insertion of a fastening 60 in said hole by the driver during a later part of the movement of the driver bar.

7. A fastening inserting implement comprising a casing formed to be held in the hand of an operator, a plunger mounted for 65 longitudinal reciprocation in the casing, a

driver carried by the lower end of the plunger, an awl bar mounted for lengthwise movement in the casing, an awl carried at the lower end of the awl bar and rigid therewith, connections between the awl bar and the 70 plunger including a latch member pivoted to the awl bar and constructed and arranged to cause the early part of the movement of the plunger toward a work piece to thrust the awl into the work piece, forming fastening receiving holes therein in alinement with the driver, a cam pivoted to the casing and operated by the continued movement of the plunger to withdraw the awl from the work piece, and means for presenting a fastening in line with 75 the hole formed by the awl in the work piece in position to be inserted by the driver by continued movement of the plunger.

8. A fastening inserting implement comprising a casing formed to be held in the hand of an operator, a reel carried by the casing and holding a coiled strip of fastening material, a manually reciprocable plunger carried by the casing, a driver carried by the plunger, and means for presenting fastenings to be inserted by the driver including a pivoted member provided with a driver passage arranged to receive the end of the strip of fastening material and gearing operated by the descent of the plunger arranged to rock said pivoted member thereby bringing said driver passage into alinement with the driver, severing a fastening from the strip of material and presenting it in position to be inserted by the driver. 90

9. A fastening inserting implement comprising a casing formed to be held in the hand of an operator, a manually operated plunger reciprocable therein, a driver carried by the plunger, an awl bar, an awl carried thereby, connections between the plunger and the awl bar constructed and arranged to reciprocate the awl bar during the early part of the reciprocation of the plunger to cause the awl to form fastening receiving holes in a work piece to which the implement is presented, and means for supplying fastenings to be inserted by the driver in the holes formed by the awl including a movable member provided with a driver passage arranged to receive the end of a strip of fastening material and for movement thereafter into alinement with the driver and with a hole formed in the work piece by the awl thereby severing a fastening from the strip of material and presenting it in position to be inserted by the driver. 100

10. Peg inserting mechanism comprising a casing having a driver passage at its lower end, a driver bar reciprocable in the casing and carrying at its lower end a driver in alinement with said driver passage, an awl positioned normally out of alinement with the driver passage, means for moving the awl into alinement with and through the 115 120 125 130

driver passage, thereby forming a fastening receiving hole in a work piece, and for thereafter withdrawing the awl from the work piece and moving it out of alinement with the driver passage, and a pivoted member for severing a peg from a strip of peg material and moving it into alinement with the driver passage and the hole formed by the awl in the work piece in position to be inserted by the driver.

11. Peg inserting mechanism comprising a casing having a driver passage at its lower end, a driver bar reciprocable in the casing toward and from a work piece and carrying at its lower end a driver in alinement with said driver passage, an awl positioned normally out of alinement with the driver passage, connections between the driver bar and the awl arranged during the early part of the movement of the plunger toward the work piece to move the awl into alinement with and through the driver passage, thereby forming a fastening receiving hole in the work piece, and thereafter withdrawing the awl from the work piece and moving it out of alinement with the driver passage, and pivoted means for shearing a peg from a strip of peg material and moving it into alinement with the driver passage and the hole formed by the awl in the work piece in position to be inserted by the driver.

12. Fastening inserting mechanism having, in combination, a casing formed and arranged to be held in the hand of an operator, a plunger reciprocable therein, a driver carried by the plunger, and means for presenting fastenings in fastening inserting relation to the driver comprising a fastening receiving member pivoted for movement from fastening receiving to fastening presenting position, a lever secured thereto and carrying a gear segment, a gear member meshing with said gear segment, and a cam member carried by the plunger and formed and arranged to rock the gear member during the reciprocation of the plunger thereby moving the fastening presenting member to present a fastening in line with the driver.

13. Fastening inserting mechanism comprising a reciprocable driver bar, a driver carried thereby, a reciprocable awl bar, an awl carried by the awl bar, connections between the driver bar and the awl bar including a latch arranged to transmit movement from the driver bar to the awl bar as the driver bar is reciprocated thereby causing the awl to penetrate a work piece, forming a fastening receiving hole therein, means for thereafter releasing the latch thereby disconnecting the driver bar and the awl bar, means for moving the awl bar in a direction to withdraw the awl from the work piece after it is disconnected from the driver bar and for thereafter moving the awl out of alinement with the hole in the work piece, and means

for presenting a fastening in alinement with the hole formed in the work piece by the awl and with the driver whereby continued movement of the driver bar and the driver is effective to cause the driver to drive a fastening into the hole.

14. Fastening inserting mechanism comprising a reciprocable driver bar, a driver carried thereby, a reciprocable awl bar, an awl carried by the awl bar, connections between the driver bar and the awl bar effective to transmit movement from the driver bar to the awl bar during the early part of the movement of the driver bar from its inoperative position toward the work piece to insert a fastening therein, and a pivoted member constructed and arranged for movement by the driver bar into engagement with a member carried by the awl bar after the awl has formed a fastening receiving hole in the work piece, said pivoted member by continued movement withdrawing the awl from the work piece and moving it out of alinement with the driver.

15. Fastening inserting mechanism comprising a casing, a reciprocable driver bar mounted for sliding movement in the casing, a driver carried thereby, a reciprocable awl bar also mounted for sliding movement in the casing, an awl carried by the awl bar, latch mechanism connecting the driver bar and the awl bar effective to transmit movement from the driver bar to the awl bar during the early part of the movement of the driver bar from its inoperative position toward a work piece to insert a fastening therein, and a cam member pivoted to the casing and constructed and arranged for movement by the driver bar into the path of movement of a member carried by the awl bar after the awl has formed a fastening receiving hole in the work piece, said cam member by continued movement withdrawing the awl from the work piece and moving it out of alinement with the driver.

16. A fastening inserting implement having, in combination, a casing formed and arranged to be held in the hand of an operator, a plunger reciprocable therein, a driven carried by the plunger, an awl bar movable in the casing, an awl carried by the awl bar, means for operating the awl bar to cause the awl to make fastening receiving holes in a work piece to which the implement is presented, and means for presenting fastenings in fastening inserting relation to the driver comprising a fastening receiving member pivoted for movement from fastening receiving to fastening presenting position, a lever secured thereto and carrying a gear segment, a gear member meshing with said gear segment, and a cam member carried by the plunger and formed and arranged to rock the gear member as the plunger is reciprocated thereby moving the fastening pre-

senting member to present a fastening in line with the driver and with a hole formed by the awl in the work piece.

17. A fastening inserting implement provided with a casing formed and arranged to be held in the hand of an operator, a plunger reciprocable therein, a driver carried by the plunger, an awl bar mounted for reciprocation in the casing, an awl carried by the awl bar, means for reciprocating the awl bar, and means for causing the awl bar to move transversely of the casing during the early part of its reciprocation thereby moving the awl into line with the driver prior to its work 10 penetrating movement and for moving the awl bar in the reverse direction at the conclusion of its return movement thereby moving the awl out of line with the driver, the awl bar reciprocating means including connections between the awl bar and the plunger constructed and arranged to cause the early part of the movement of the plunger to move the awl bar thereby causing the awl to penetrate a work piece to which the implement is 20 presented, and means for thereafter breaking the connection between the awl and the awl bar thereby permitting the return of the awl bar to inoperative position.

18. A fastening inserting implement provided with a casing formed and arranged to be held in the hand of an operator, a plunger reciprocable therein, a driver carried by the plunger, an awl bar mounted for reciprocation in the casing, an awl carried by the awl bar, connections between the plunger and the awl bar including a latch arranged to transmit movement from the plunger to the awl bar during the early part of the movement of the plunger toward a work piece to which the implement is presented to cause the awl to form a fastening receiving hole in the work piece, means for releasing said latch, means for returning the awl bar to its original position when the latch is released, means for 30 causing the awl bar to move transversely of the casing during the early part of its movement toward the work piece thereby moving the awl into line with the driver prior to its work penetrating movement and for moving the awl bar in the reverse direction at the conclusion of its return movement thereby moving the awl out of line with the driver, and means for presenting a fastening in 40 alinement with the hole formed in the work piece by the awl and with the driver whereby continued movement of the plunger is effective to cause the driver to drive the fastening into the hole.

19. Fastening inserting mechanism comprising a reciprocable driver bar, a driver carried thereby, a reciprocable awl bar, an awl carried by the awl bar, connections between the driver bar and the awl bar including a latch pivoted to the awl bar and arranged to engage a latch surface on the driver

bar to transmit movement from the driver bar to the awl bar as the driver is reciprocated thereby causing the awl to penetrate a work piece forming a fastening receiving hole therein, a cam member arranged to engage a cam surface on said latch when the hole has been made thereby moving the latch out of engagement with the latch surface of the driver bar and thereby disconnecting the driver bar and the awl bar, a pivoted cam 70 rocked by further movement of the driver bar thereby moving the awl bar in a direction to withdraw the awl from the work piece and subsequently moving the awl out of alinement with the hole in the work piece, and means for presenting a fastening in alinement with the hole formed in the work piece by the awl and with the driver whereby continued movement of the driver bar and the driver is effective to cause the driver to drive 80 a fastening into the hole.

20. Fastening inserting mechanism comprising a driver bar, a driver carried thereby, an awl bar, an awl carried thereby, connections between the driver bar and the awl bar constructed and arranged to transmit movement from the driver bar to the awl bar during the early part of the movement of the awl bar toward a work piece thereby moving the awl bar and the awl toward the work 90 piece and causing the awl to form a fastening receiving hole therein, means for presenting fastenings in fastening inserting relation to the driver and the hole formed in the work piece by the awl including a 100 fastening receiving member pivoted for movement from fastening receiving to fastening presenting position, a lever secured thereto and carrying a gear segment, a gear member meshing with said gear segment, a cam member carried by the driver bar and formed and arranged to rock the gear member during the reciprocation of the plunger thereby moving the fastening presenting member to present a fastening in line with the driver, said awl bar being provided with a projection positioned in the path of movement of a cam surface formed on said gear member whereby the rocking of the gear member to bring the fastening receiving member into fastening presenting position is effective also to withdraw the awl from the work piece.

21. Fastening inserting mechanism provided with a plunger movable toward a work piece through a normally predetermined path, a driver carried by the plunger, a spring tending to move the plunger to its inoperative position, a latch block carried by the plunger, a latch member operative to engage the latch block thereby preventing the return of the plunger to its inoperative position when it has been moved therefrom through less than its complete normal path, a slide bar operated by the plunger and longitudinal move- 120 125 130

ment of which renders the latch member inoperative to engage the latch block as the plunger completes its movement toward the work piece.

22. Fastening inserting mechanism including a driver bar movable toward and from a work piece through a normally predetermined path, a driver carried by the driver bar, means tending to move the driver bar to its inoperative position, a latch block carried by the driver bar and provided with a plurality of transverse grooves, a latch member past which the grooves move as the driver bar is moved toward the work piece whereby the return of the driver bar to the work piece is prevented by the engagement of the latch member in one of the slots if such return movement starts to take place before the driver bar is moved through its complete normal path, and means for moving the latch member out of the path of movement of said latch block as the driver bar completes its movement toward the work piece.

23. Fastening inserting mechanism including a driver bar movable toward and from a work piece through a normally predetermined path, a driver carried by the driver bar, a spring tending to move the driver bar to its inoperative position, a latch block carried by the driver bar and provided with a plurality of transverse grooves, a yielding latch member past which the grooves move as the driver bar is moved toward the work piece whereby the return of the driver bar to the work piece is prevented by the engagement of the latch member in one of the slots if such return movement starts to take place before the driver bar is moved through its complete normal path, a slide bar movable to render the latch member inoperative, and means for moving the slide bar as the driver bar completes its movement toward the work piece thereby rendering the latch member inoperative and permitting the return of the driver bar to its original position.

In testimony whereof I have signed my name to this specification.

FRED N. LA CHAPELLE.
